UNITED STATES PATENT OFFICE.

GEORGE W. COLLINS, OF HOLYOKE, MASSACHUSETTS.

DESIGN FOR A CHAIR.

42,618.

Specification for Design.

Patented June 18, 1912.

Application filed June 4, 1910. Serial No. 565,118. Term of patent 7 years.

To all whom it may concern:

Be it known that I, GEORGE W. COLLINS, a citizen of the United States, residing at Holyoke, in the county of Hampden and State of Massachusetts, have invented a new, original, and ornamental Design for Chairs, of which the following is a specification, reference being had to the accompanying drawing, forming part thereof.

The figure is a perspective view of a chair, showing my new design.

I claim:

The ornamental design for a chair, as shown.

GEORGE W. COLLINS.

Witnesses:

P. A. STONE,

R. M. BELVILLE.
